UNITED STATES PATENT OFFICE.

EDWARD W. GERRISH, OF WEST LYNN, MASSACHUSETTS.

HINGED LAST.

Application filed October 16, 1926. Serial No. 141,923.

This invention relates to hinged lasts and has for its object the production of a last of this character which will be simple in construction, effective in operation, and easily assembled.

This object is attained by the mechanism of last illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a longitudinal vertical section of a last embodying the principles of the present invention and in extended position.

Figure 2 represents a vertical section of same on line 2, 2 on Fig. 1.

Figure 3 represents a horizontal section of a portion of same on line 3, 3, on Fig. 1, before one of the securing pins has been driven through the hinge members.

Figure 4 represents a longitudinal vertical section of the last in its shortened position.

Figure 5 represents a side elevation of one of the hinge plates.

Figure 6 represents an end elevation of the same.

Figure 7 represents a side elevation of the other hinge plate, and

Figure 8 represents a vertical section of same on line 8, 8 on Fig. 7.

Similar characters indicate like parts throughout the several figures of the drawings.

In the drawings, 10 and 11 represent respectively, a fore part and a heel part of a last divided on a substantially vertical line and having a transverse V-shaped notch 12 in the upper part thereof.

The parts 10 and 11 have cut therein the grooves 13 and 14 in which is inserted the hinge 15 by which said fore part 10 and heel part 11 are connected together.

This hinge 15 is made up of two plates 16 and 17, each of which is provided with an

opening therethrough. The opening 18 in the plate 16 is adapted to receive the annular transverse extension 19 surrounding the smaller opening 20 formed in the plate 17.

This extension 19 is punched up from the metal plate 17 and after it has been positioned within the opening 18 its end is upset as at 21 to form a flange or shoulder disposed in the recess 22 in the plate 16 and serving to prevent the separation of the two hinge plates 16 and 17.

It is obvious that a hinge thus constructed is very strong and the extension 19 makes a very effective pivot about which the plate 16 may freely move.

In the opening 20 of the plate 17 is disposed a hinge pin 23 which is driven therein so tightly that the plate 17 and hinge pin 23 are immovable relatively to each other.

The opposite ends of the hinge pin 23 extend beyond the outer faces of the plates 16 and 17 and are positioned in semi-cylindrical depressions 24 formed in the opposed faces of the fore part 10 and heel part 11.

These semi-cylindrical depressions 24 extend transversely of these opposed faces and are perpendicular to the side walls of the grooves 13 and 14.

Each plate 16 and 17 is provided with a cylindrical hole 25 adapted to receive a securing pin 26, one of these securing pins being in the heel part 11 and locking the plate 17 therein while the other securing pin 26 is adapted to lock the plate 16 in the groove 13 of the fore part 10.

The cylindrical holes 25 in the plate 16 and 17 are at one side of the centers thereof, while on the opposite side of said centers these plates are provided with concentric grooves 27.

The lower ends of these grooves 27 have a width equal to the diameter of the securing pins 26, but at their upper ends 28 these grooves are of slightly less width than the diameter of said pins so that when a securing pin 26 enters this narrow end 28 it will be jammed between the walls thereof and be locked therein until force is applied to remove it therefrom.

In other words, when it is desired to break or shorten the last the securing pins 26 will move freely in these slots 27 until they nearly reach the upper ends thereof when they will be jammed into the narrow portion 28 of the slots and lock the fore part

10 and heel part 11 in the position indicated in Fig. 4, keeping the last in this position in readiness for the operator to insert said last into a shoe.

5 The fore part 10 is provided with a long socket 29 in which is disposed one end of a helical spring 30, the opposite end of which extends into a short socket 31 in the heel part 11.

10 Under normal conditions this spring 30 keeps the parts 10 and 11 in their extended position, as indicated in Fig. 1, with the lower opposed faces of the fore part and heel part in contact.

15 The spring 30 has sufficient tension to force the toe and heel part into position when the securing pins 26 are freely movable in the slots 27, but this tension is insufficient to move the parts 10 and 11 relative to each other when the securing pins 26 are jammed into the narrow portions 28.

The upper and lower ends of the vertical grooves 13 and 14 formed in the opposed faces of the toe part 10 and heel part 11 25 terminate between the tops and bottoms of the parts 10 and 11. By doing this, the bottom of the last is free from any slot extending therethrough leaving a solid unbroken surface when the last is extended.

30 The spring 30 crosses the notch 12 adjacent to one face of the plate 17, said plate forming a protection for said plate.

Owing to the location of the spring adjacent to the side face of the plate 17 and 35 near the axis of the hinge pin 23, the spring 30 cannot be easily tampered with and dislodged from its sockets 29 and 31.

The plates 16 and 17 accurately fit the grooves 13 and 14 with their outer walls 40 contacting with the walls of these grooves 13 and 14, so that lateral play of the fore part 10 and heel part 11 is effectually prevented.

The projecting ends of the hinge pin 23 45 disposed in the semi-cylindrical depressions 24 also assists in preventing any lateral play between the two parts 10 and 11.

The inner ends of the securing pins 26 are tapered as shown at 32 so that when 50 driven through the cylindrical opening 25 and concentric grooves 27, they will force the projecting ends of the hinge pin 23 into firm contact with the bottoms of the semi-cylindrical depressions 24.

55 This feature is of considerable importance, as in order to secure a rigid last under all conditions it is quite essential that the entire periphery shall be in close contact with the walls of the semi-cylindrical grooves 24.

60 When assembled the plate 17 and the hinge pin 23 are immovable relatively to the heel part 11 and in breaking the last the plate 16 moves about the periphery of the annular flange 19 formed upon the plate 17.

65 During this shortening movement each

of the securing pins 26 move toward the upper ends of the slots 27 and when they reach the position indicated in Fig. 4 they become jammed between the walls of the narrow portion 28 and retain the last in 70 shortened position, as shown in said Fig. 4.

When the last in this position is inserted within a shoe pressure applied to one of the parts of the last will force the pins 26 75 out of the narrow portion 28 and permit the spring 30 to effect a lengthening of the last.

This makes a very effective last which is simple in construction and easily assembled. When assembled it has great rigidity 80 and there is no opportunity for any lateral play between the two parts thereof.

It is believed that the operation and 85 many advantages of the invention will be understood without further description.

Having thus described my invention, I claim—

1. A last consisting of a fore part and a heel part having aligned vertical slots and transverse semi-cylindrical depressions in 90 their opposed faces; vertical plates secured one in each part and overlapping each other, and one movable relatively to the other; and a pivot pin immovably positioned in one of said plates with its opposite ends extending beyond the outer faces of said plates and disposed in said depressions.

2. A last consisting of a fore part and a heel part having aligned vertical slots and transverse semi-cylindrical depressions in 100 their opposed faces; vertical plates secured one in each part and overlapping each other, one plate having an annular flange extending through the other plate, said other plate being freely rotatable upon said flange; and a pivot pin immovably secured to said flanged plate with its ends disposed in 105 said depressions.

3. A last consisting of a fore part and a heel part having aligned vertical slots and transverse semi-cylindrical depressions in 110 their opposed faces; vertical plates secured one in each part and overlapping each other, one plate having an annular flange extending through the other plate, said other plate being freely rotatable upon said flange; a pivot pin immovably secured to said flanged plate with its ends disposed in said depressions; and means formed in said plates and coacting with the securing means therefor whereby said pin ends may be forced into contact with the walls of said depressions.

4. A last consisting of a fore part and a heel part having aligned vertical slots and transverse semi-cylindrical depressions in 115 their opposed faces; vertical plates secured one in each part and overlapping each other, one plate having an annular flange extending through and terminating at the outer face of the other plate and each plate hav- 120

130

ing a concentric slot in its projecting end through which extends the securing pin of the other plate; and a pivot pin secured to said flanged plate with its ends projecting beyond the outer faces of said plate and disposed in said depressions.

5. A last consisting of a fore part and a heel part having alined vertical slots and transverse semi-cylindrical depressions in their opposed faces; vertical plates secured one in each part and overlapping each other, one plate having an annular flange extending through the other plate and each plate having a concentric slot in its projecting end through which extends the securing pin of the other plate and the upper end of each slot having a width less than that of its lower end whereby the securing pins may be wedged in the narrow ends of the slots and retain the fore part and heel part in shortened position; and a pivot pin secured to said flanged plate with its ends disposed in said depressions.

6. A last consisting of a fore part and a heel part having alined vertical slots and transverse semi-cylindrical depressions in their opposed faces; vertical plates secured one in each part and overlapping each other and one movable relatively to the other; a pivot pin immovably positioned in one of said plates with its ends disposed in said depressions; and a spring between said parts adjacent the side of one of said plates.

7. A last consisting of a fore part and a heel part having alined vertical slots and transverse semi-cylindrical depressions in their opposed faces, said slots terminating within the top and bottom walls of said parts; vertical plates secured one in each part and overlapping each other and one movable relatively to the other; and a pivot pin immovably positioned in one of said

plates with its ends disposed in said depressions on opposite sides of said plates.

8. A last consisting of a fore part and a heel part having alined vertical slots and transverse semi-cylindrical depressions in their opposed faces; vertical plates secured one in each part and overlapping each other and one movable relatively to the other; a pivot pin immovably positioned in one of said plates with its ends disposed in said depressions on opposite sides of said plates; and a helical spring between said parts adjacent the side of one of said plates with its ends disposed in sockets in said opposed faces.

9. A last consisting of a fore part and a heel part having alined vertical slots and transverse semi-cylindrical depressions in their opposed faces; vertical plates secured one in each part and overlapping each other, one plate having an annular flange extending through the other plate with its outer end upset in a recess in said other plate which plate is rotatable freely upon said flange; and a pivot pin secured to said flanged plate with its ends disposed in said depressions on opposite sides of said plates.

10. A last consisting of a fore part and a heel part connected together by a hinge consisting of two plates and pivotally connected by an annular flange on one plate extending through a cylindrical opening in the other plate with its outer end upset disposed in alined vertical slots in said parts, each plate having a cylindrical hole for the reception of a securing pin in one part, and a concentric slot through which extends the securing pin of the other part.

Signed by me at 746 Old South Bldg., Boston, Mass., this 5th day of October, 1926.

EDWARD W. GERRISH.
